UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,386,786.

Specification of Letters Patent.

Patented Aug. 9, 1921.

Application filed October 29, 1919. Serial No. 334,259.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 This invention relates to typographical machines, such as linotype machines of the general organization represented in Letters Patent No. 436,532 to O. Mergenthaler, wherein circulating matrices are released 15 from a magazine in the order in which their characters are to appear in print and then assembled in line, the composed line transferred to the face of a mold, the mold filled with molten metal to form a slug or linotype 20 against the matrices which produce the type characters thereon, and the matrices thereafter elevated and returned through distributing mechanism to the magazine from which they started. More particularly, it relates to machines equipped with a plurality 25 of magazines containing matrices of different font or face, and any selected one of which may be brought into action at will.

In one class of such machines, the magazines 30 are arranged in constant operative relation to a corresponding plurality of distributors (which may thus distribute the matrices into all of them simultaneously) and are movably arranged so that any selected one may be brought into operative 35 relation to the assembling devices, the arrangement being such that the movement of the magazines may take place without disturbing their relation to the respective distributors. Such a machine for example is 40 illustrated in the Muehleisen U. S. Patent No. 1,031,952.

The present invention is primarily directed to various improvements in machines of this class, although some of them 45 would be useful in other kinds of machines as well. These improvements will be fully pointed out in the detailed description to follow.

50 Referring to the drawings:

Figure 1 is a side elevation of a linotype machine having my improvements embodied therein;

55 Fig. 2 is a similar view showing the parts in different position;

Fig. 3 is a similar view taken at the lower part of the magazines, showing the parts in a still different position and with one of the magazines removed;

Fig. 4 is a section taken on the line 4—4 60 of Fig. 1 looking in the direction of the arrow;

Fig. 5 is an end view of one of the magazines with its associated escapement frame, showing in detail the mechanism for holding 65 the latter in operative relation to the magazine;

Fig. 6 is a rear elevation, taken at opposite sides, of the parts shown in Fig. 1 with the distributing mechanism omitted;

Fig. 7 is a side elevation taken at the left of the upper portion of the machine shown in Fig. 1.

The matrices X are stored according to font in the superposed magazines A, only 75 two of which are herein shown but of which a greater number might be employed if desired. These magazines are supported upon the customary base frames A¹ conjointly constituting a shift-frame which, as 80 later to be described, is arranged to be swung upwardly and downwardly in the machine to locate either magazine in operative relation to the fixed assembler entrance or raceway B. Each magazine is provided 85 with escapements C which, when that magazine is in operative position, are engaged and actuated by the pivoted levers C¹ operated by the reeds C² under the control of the keyboard C³ in the regular way. After assemblage and casting, the matrices are carried upward and delivered to the font separator D which assorts them according to font and drops them into one or the other of the tubes D¹ leading to the two distributors E, whereby they are separated according to character and returned through one or the other of the magazine entrances F to the magazine A from which they started.

The front separator D is of well known 100 form, being the same as employed in the commercial "model 9" linotype or as illustrated in Rogers U. S. Letters Patent No. 848,771. The arrangement of the two distributors E, however, is as illustrated in 105 the Muehleisen U. S. Letters Patent No. 1,221,360; that is to say, they are arranged stepwise one above another from front to rear of the machine so that the magazine entrances F may be swung rearwardly to give 110

- access to the interior parts without having first to swing the distributor upwardly out of the way. In this connection, it may be noted that the two magazine entrances F are pivoted, as at F¹, to the respective base frames A¹, the upper entrance being held in place by the customary spring F¹¹, and the lower entrance by an improved spring arrangement later to be described.
- 10 The improvements first to be described deal with the mounting of the magazines whereby they may be swung upwardly and downwardly for interchange without disturbing their connection through the respective magazine entrances with the corresponding distributors. To this end, following the Muehleisen Patent No. 1,031,952 before mentioned, the base frames A¹ are pivotally mounted at their upper ends so as to turn about independent axes located below and close up to the distributors in such manner that when the base frames are swung about their respective axes, the extent of rocking of the magazine entrances F at their upper or receiving ends will be so slight as not to interfere with their operative relation to the distributors, which may thus continue to distribute the matrices into the magazines at all times. In the present instance, however, and unlike the arrangement shown in the above Muehleisen patent, the axes of rotation of the two magazine base frames are arranged one behind the other in the longitudinal plane of the uppermost magazine, this arrangement being found to be more satisfactory for the intended purpose. The mounting of the base frames has also been improved upon as follows:
- 40 Each of the base frames A¹ is provided at opposite sides with a pair of rearwardly extending arms A² and A⁴, both offset laterally from the frame (Fig. 6) so as to allow the magazine entrance F to be pivoted thereto in the manner before described.
- 45 The arms A² remain spaced from the magazine entrances and are fixed at their upper ends to pivot pins A³ journaled in suitable bearings of a supporting bracket O², which latter is attached to one of the vertical arms 50 of the customary U-shaped distributor frame O. On the other hand, the arms A⁴, after passing the pivotal points F¹ of the magazine entrances, are turned inwardly toward and extended upwardly directly alongside the entrances, being formed at their extremities with flat circular head portions A⁵ fitting in corresponding sockets of an overhanging supporting plate O⁴ (Fig. 7). This plate O⁴ is located in the plane of the 55 uppermost portions of the arms A⁴ and is extended downwardly between them, where it is fastened by screws or otherwise to the inner face of a laterally curved supporting bracket O⁵ attached to the other vertical 60 arm of the distributor frame O. This pecu-

iar arrangement of the arms A⁴ and their supporting bracket is made so as to allow the magazine base frames to be pivoted as close up to the distributors as possible without interfering with the feed devices or distributor boxes of the two distributors E, it being well known that such distributor boxes are located below the distributors and immediately adjacent the receiving ends thereof. It will be seen, therefore, that the pivotal axis of each magazine is made up in part of the pin A³ and the circular head portion A⁵, which parts of course are arranged in transverse alignment. As thus mounted, the magazines are free to be rocked upwardly and downwardly about their pivotal axes so that either one may be brought into operative position, it being observed such axes are located sufficiently close to the distributors to maintain the magazine entrances in proper receiving relation thereto in either position of the magazines.

As the magazines partake of a relative movement when swung upwardly and downwardly, means are provided to permit such relative movement of the parts while preserving their proper relation to each other when in closed condition. Such means are in the form of a pair of gage pieces A⁶ depending from the upper magazine base frame and resting directly upon plain alining surfaces A⁷ on the upper face of the underlying base frame (see particularly Fig. 4). To maintain the two base frames in proper lateral relation to each other, the gage pieces A⁶ are formed with extensions or lips A⁸ fitting into corresponding notches in the upper face of the lower base frame, the vertical side walls of such notches thus constituting further alining surfaces which are engaged laterally by the gage pieces. It should be noted that, due to the free engagement of the gage pieces with the alining surfaces, the two base frames may be separated or spread apart at will, a feature later to be described.

The swinging of the shift frame to effect the interchange of the magazines may be effected in any desired manner. The means herein employed consist essentially of a toggle system which when straightened or extended raises the shift frame to place the lower magazine in operative position and when collapsed allows the frame to swing downwardly to bring the upper magazine in such operative position. In the latter position, the shift frame or the lower base frame thereof banks upon a pair of set screws A¹¹ which are adjusted to locate the upper magazine in registration with the assembler entrance B, the set screws being mounted on the parallel side arms O⁵ of a U-shaped bracket O¹ attached to the distributor frame O. The shift frame is supported in its raised position directly by the

toggle system which is designed when straightened to locate the lower magazine in correct registration with the assembler entrance. The foregoing toggle system 5 comprises two pairs of links H and H^1 intermediately connected by a transverse rod H^2 to which the lower members H^1 are made fast and on which the upper members H are loosely mounted (Fig. 4). At their 10 lower ends, the members H^1 are pivoted by pins or screws H^3 to the side members O^5 of the U-shaped bracket O^1 just referred to; and at their upper ends, the members H are formed with open bearings or forks h where- 15 in engage pins A^{10} projecting inwardly from lugs A^9 depending from the lower base frame A^1 . The rod H^2 is guided in curved slots O^7 of the bracket arms O^5 and is movable therein to effect the extension or col- 20 lage of the toggle members H and H^1 for raising and lowering the magazines as required, the rod being limited in its movements by the end walls of the slots, the forward ends of which are arranged to permit 25 the rod to pass "dead center" so as to lock the magazines in their raised position. Such movement of the rod H^2 is controlled by a hand lever pivoted at H^6 to the machine frame and having its shorter arm H^4 30 engaged with one end of the rod and its longer arm H^6 extended forwardly and downwardly within reach of the operator while seated at the keyboard. As a result of this construction when the lever arm H^6 35 is depressed, the rod H^2 is drawn forwardly to straighten the toggle members H and H^1 , which thereby raise the shift frame and bring the lower magazine into operative relation to the fixed assembler entrance B and the escape- 40 ment actuating levers G^1 (Fig. 1). On the other hand, when the lever arm H^6 is raised, the rod H^2 is shifted rearwardly to collapse the toggle members H and H^1 and allow the shift frame to swing downwardly until ar- 45 rested by the engagement of the lower base frame A^1 with the screws A^{11} , in which position of the parts, the upper magazine is located in operative relation to the assembler entrance B and escapement actuat- 50 ing levers C^1 (Fig. 2). To prevent the too hasty collapse of the toggle members, the rod H^2 is connected by an arm H^7 and link H^8 to the piston H^9 of a dash-pot H^{10} (Fig. 2), although any other suitable form 55 of cushioning means might be employed for the purpose.

Further improvements provide mechanism whereby the individual magazines may be speedily removed independently from the 60 front of the machine. The preferred method employed is to raise the entire magazine structure upwardly to an extent sufficient to locate the lower magazine above the level of the fixed assembler entrance and 65 simultaneously to separate the magazines

vertically from each other. In the present instance, the raising of the magazine structure is effected by means distinct from or additional to the shifting means just described for swinging the magazines upwardly and 70 downwardly to locate either in operative position, it being noted that the extent of action of the shifting means is only sufficient to locate the lower magazine in operative relation to the assembler entrance. The 75 magazine raising means herein illustrated comprise a pair of rotary cams J fixed to the opposite ends of a transverse rock shaft J^1 journaled in suitable bearings of the lower base frame A^1 . These cams are ar- 80 ranged to coöperate with rollers O^{10} carried by a pair of brackets O^9 attached to the distributor frame O and are rotated by an operating handle J^3 , which may be made integral with one of the cams as herein shown 85 or attached separately to the rock shaft J^1 . Normally and when at rest, the cams J stand clear of the rollers O^{10} so as to permit the free and unimpeded shifting of the magazines, but upon the operation of the hand 90 lever J^2 , the cams are brought into engagement with the rollers and then by their continued rotation swing the entire magazine structure upwardly about the pivotal axes of the respective base frames to an extent 95 sufficient to locate the lower magazine above the assembler entrance B (see Fig. 3). However, and as before stated, it is also proposed to effect the vertical separation of the magazines as they are thus raised, and to this 100 end, the cams J are pivotally connected by links J^2 to the upper base frame A^1 , the points of attachment of the links to the cams being such that the connected frame will be swung upwardly about its pivotal 105 axis to a further extent than that of the underlying base frame so as thus to separate the two base frames from each other (Fig. 3). In other words, to effect the removal of the magazines, it is merely necessary to draw the operating handle J^3 forwardly from the position shown in Fig. 1 to that indicated by the dotted lines therein and illustrated by the full lines in Fig. 3, by which single operation, the two magazines are not only located above the fixed assembler entrance B but at the same time are separated from each other, so that either one may be drawn forwardly from the machine and replaced by another containing 110 115 120 matrices of a different font.

Counterbalancing means are employed to assist the operator in performing the above operations. As shown, the rock shaft J^1 has fast thereto an arm J^4 pivoted to the forward end of a lever J^5 centrally pivoted at J^6 to a bracket O^{11} on the distributor frame O and having its rear end connected to the upper end of a strong spiral spring J^7 whose lower end is anchored to the bracket O^{11} . 130

As the parts are so arranged, the spring J^7 is enabled to exert a turning movement upon the rock shaft J^1 when the cams J are engaged with the rollers O^{10} and thus materially assists in the operation of raising and separating the magazines. When the cams J are at rest and out of engagement with the rollers O^{10} , such turning force of the spring J^7 is not allowed to exert itself by reason of the position of the arm J^4 , whose pivotal point of connection with the lever J^5 at that time is directly in line with the shaft J^1 . However, in this condition of the parts, the spring exerts a lifting force, which though insufficient to overcome the entire weight of the magazine structure, materially assists the operator in shifting the magazines to effect their interchange.

It will have been understood that the raising of the magazines to a position beyond that controlled by the shifting means is permitted by the free connection between the upper toggle members H and the lower magazine base frame, it being remembered that this connection is made by forming each toggle member at its upper end with an open bearing or fork h wherein the pin A^{10} on the base frame engages. Consequently, the magazines are free to be moved relatively to their shifting means whenever they are to be removed. When the magazines are so moved, it is essential that the toggle members remain in their extended condition so that their connection with the shift frame will be reestablished when the frame is subsequently lowered into place. For this reason, the two bracket arms O^5 are provided with stop pins O^6 (Fig. 4) arranged to engage the forward edges of the upper toggle members H well above the rod H^2 and to coöperate with hooks or projections h^1 formed thereon. Under this arrangement, when the toggle members H are disengaged from the pivot pins A^{10} of the lower base frame, they will be prevented from falling forwardly by their engagement with the stop pins O^6 , and in addition if an attempt be made to move the rod H^2 rearwardly to collapse the toggles, this will be prevented by the engagement of the stop pins with the hooks h^1 , see dotted lines in Fig. 3, thereby locking the magazine shifting means against operation.

As in my previous Letters Patent No. 1,304,689, the escapements C , instead of being attached directly to the magazines, are mounted in frames C^4 pivotally attached to the base frames. Each of the frames C^4 is held in operative relation to the respective magazine by a pair of latches C^6 pivotally mounted in the upper ends of the laterally swinging arms C^5 , which latter are locked in sustaining position by detents, controlled by the usual matrix locking bar. In the patent, the latches C^6 are actuated

by springs, which it has been found, become weakened in use and allow the escapement frame to sag. In the present instance, therefore, the swinging arms C^5 are provided with adjusting means to hold the latches C^6 in positive and unyielding engagement with the magazine. To this end, the latches C^6 are made in the form of small bell-crank levers centrally pivoted to the arms C^5 and having their horizontal arms arranged to engage the upper side plate of the magazine. The vertical arms of the latches are located in suitable recesses in the arms C^5 and have pivoted thereto laterally projecting pins C^8 connected by screw threads to adjusting nuts C^7 bearing against raised portions of the arms C^5 . In detaching the escapements, therefore, the nuts C^7 are first unscrewed to relieve the pressure of the latches on the magazine, and in restoring the parts to operative position, the nuts are again screwed up to bind the latches against the magazine. In this connection, it will be remembered that the magazines are separated or spread apart preparatory to their removal, so that there is ample space between them to permit the downward movement of the escapement-frames as required (see dotted lines in Fig. 1).

The improved spring arrangement for holding the lower magazine entrance in operative position will now be described. This arrangement comprises, a pair of torsion springs F^2 encircling a transverse rock shaft F^3 provided at opposite ends with journal studs F^4 rotating in bearings F^5 of the entrance frame. At their inner ends the springs are connected to collars F^9 fixed on the shaft and have their outer ends made in the form of hooks to engage the ribbed members of the entrance frame. Beyond the bearings F^5 , the journal studs F^4 have fast thereto cap portions or bosses F^6 provided with arms F^7 carrying rollers F^8 arranged in engagement with the underside of the base frame A^1 of the lower magazine. These arms F^7 by reacting against the magazine base frame thus maintain the springs F^2 under sufficient tension to hold the entrance up in its operative position, and at the same time permit it to be turned downwardly about its pivot F^1 to give access to the interior parts. As the entrance is swung downwardly (Fig. 2), the arms F^7 roll along the under side of the base frame and, by rotating the shaft F^4 , place the springs F^2 under greater tension, so that when the entrance is released it is immediately restored to operative position by the springs. If desired, a tubular casing F^{10} may be employed to inclose the parts for the exclusion of dust and foreign particles.

As previously stated, I have shown my improvements only in preferred form and by way of example and as applied to a par-

ticular class of linotype machines, but obviously many modifications and alterations therein and in their mode of application will suggest themselves to those skilled in the art without departure from the scope of the invention.

Having thus described my invention, its construction and mode of operation, what I claim and desire to secure by Letters Patent of the United States is as follows:—

1. In a typographical machine, the combination of a plurality of distributers, a corresponding plurality of magazines, each mounted to turn about a separate and independent pivotal axis located immediately adjacent the corresponding distributer, and means for swinging the magazines about their respective pivotal axes to bring one or another into operative position, the said pivotal axes being arranged substantially in the longitudinal plane of the uppermost magazine.

2. In a typographical machine, the combination of a plurality of distributers, a corresponding plurality of magazines, separate base frames carrying said magazines and each mounted to turn about a separate and independent pivotal axis located immediately adjacent the corresponding distributer, and magazine entrances also carried by the base frames to conduct the matrices from the distributers to the respective magazines, each of said entrances being separately pivoted to the corresponding base frame so as to be swung downwardly to give access to the interior parts.

3. In a typographical machine, the combination of a plurality of distributers, a corresponding plurality of magazines, separate base frames carrying said magazines, magazine entrances pivotally connected to the base frames, and supporting arms extending rearwardly from each base frame and pivoted at their upper ends immediately adjacent the corresponding distributer, said arms being offset from the respective base frames to clear the pivotal points of the magazine entrances.

4. In a typographical machine, the combination of a plurality of distributers, a corresponding plurality of magazines, intermediate magazine entrances to carry the matrices from the former to the latter, separate base frames carrying the magazines and their respective entrances, and supporting brackets wherein the base frames are separately and independently pivoted at their upper ends immediately adjacent the corresponding distributers, one of said brackets lying directly alongside the entrances to avoid interference with the matrix feed mechanism associated with the distributers.

5. In a typographical machine, the combination of a plurality of distributers, a corresponding plurality of magazines, inter-

mediate magazine entrances to carry the matrices from the former to the latter, separate base frames carrying the magazines and their respective entrances and each provided with a pair of rearwardly extending arms, and supporting brackets wherein said arms are pivoted at their upper ends, the arms at one side having their uppermost portions lying in the same vertical plane as the supporting bracket to which they are pivoted.

6. In a typographical machine, the combination of a plurality of distributers, a corresponding plurality of magazines, intermediate magazine entrances to carry the matrices from the former to the latter, separate base frames carrying the magazines and their respective entrances and each provided with a pair of rearwardly extending arms, and supporting brackets wherein said arms are pivoted at their upper ends, the arms at one side having their uppermost portions lying in the same vertical plane as their supporting bracket and connected thereto by circular-head-and-socket joints.

7. In a typographical machine, the combination of a plurality of distributers, a corresponding plurality of magazines, intermediate magazine entrances to carry the matrices from the former to the latter, separate base frames carrying the magazines and their respective entrances and each provided with a pair of rearwardly extending arms, and supporting brackets to which said arms are pivotally connected at their upper ends, the pivotal connection at one side being in the form of circular-head-and-socket joints for the purpose described.

8. In a typographical machine, the combination of a magazine, a distributer, an intermediate pivoted magazine entrance, a torsion spring carried bodily by the entrance and a movable device connected to said spring and arranged to react against a relatively fixed part of the machine to maintain the entrance in operative position.

9. In a typographical machine, the combination of a magazine, a distributer, an intermediate pivoted magazine entrance, a rock shaft carried by the entrance, a torsion spring surrounding the shaft and connected thereto at one end and at its opposite end to the entrance, and an arm fixed to the shaft and arranged in engagement with a relatively fixed part of the machine to cause the spring to maintain the entrance yieldingly in operative position.

10. In a typographical machine, the combination of a magazine, a base frame whereon the magazine is mounted, a magazine entrance pivoted to said base frame, a rock shaft carried by the entrance, a torsion spring surrounding the shaft and connected thereto at one end and at its other end to the entrance, and an arm fixed to the shaft and

contacting with the under side of the base frame to cause the spring to hold the entrance yieldingly in operative position.

11. In a typographical machine, the combination of a magazine, an escapement frame supported independently thereof, a sustaining arm rising from the frame, a bell crank latch centrally pivoted to the upper end of the sustaining arm and having its horizontal arm arranged to engage the magazine, a laterally projecting pin pivoted to the vertical arm of said latch, and an adjusting nut threaded to said pin and bearing against the sustaining arm to set and maintain the latch in positive and unyielding engagement with the magazine.

12. In a typographical machine, the combination of a fixed assembler entrance, a plurality of magazines, a shift frame movable to bring one or another of the magazines into operative relation to the assembler entrance and comprising base frames wherein the magazines are removably mounted, means for effecting such movement of the shift frame, additional means for moving the shift frame relatively to the shifting means to locate the lowermost magazine beyond the assembler entrance, and connections actuated by said additional means for separating the base frames from each other.

13. In a typographical machine, the combination of a fixed assembler entrance, a plurality of magazines, separate base frames whereon the magazines are removably mounted, means for shifting the base frames to bring one or another of the magazines into operative relation to the assembler entrance, additional means connected to the lowermost base frame to move it relatively to the shifting means to locate the magazine thereon beyond the assembler entrance, and means actuated by said additional means and connected to an upper base frame for separating the latter from the underlying magazine.

14. In a typographical machine, the combination of a fixed assembler entrance, a plurality of magazines, a shift frame wherein the magazines are removably mounted and movable to bring one or another thereof into operative relation to the assembler entrance, means for effecting such movement of the shift frame, and additional means carried by the shift frame for moving it relatively to the shifting means to locate the lowermost magazine beyond the assembler entrance, the said additional means when at rest being arranged to permit the free and unimpeded movements of the shift frame under the action of the shifting means.

15. In a typographical machine, the combination of a fixed assembler entrance, a plurality of magazines, a shift frame wherein the magazines are removably mounted and movable to bring one or another thereof

into operative relation to the assembler entrance, means for effecting such movement of the shift frame, and a pair of cams mounted on and carried by the shift frame and arranged to coöperate with rollers on the machine frame to move the shift frame relatively to the shifting means to locate the lowermost magazine beyond the assembler entrance, the said cams when at rest being disengaged from their coöperating rollers so as to permit the free and unimpeded movements of the shift frame under the action of the shifting means.

16. In a typographical machine, the combination of a fixed assembler entrance, a plurality of magazines, separate base frames whereon the magazines are removably mounted, means for shifting said base frames to bring one or another of the magazines into operative relation to the assembler entrance, additional means mounted on and carried by the lower base frame for moving it to an extent sufficient to locate the magazine thereon beyond the assembler entrance, and connections actuated by said additional means for separating the base frames from each other.

17. In a typographical machine, the combination of a fixed assembler entrance, a plurality of distributor, a corresponding plurality of magazines operatively connected with the distributor, separate base frames whereon the magazines are removably mounted and each pivotally mounted at its upper end immediately adjacent the corresponding distributor, means for shifting the base frames about their respective pivots to bring one or another of the magazines into operative relation to the assembler entrance without affecting the connection of the magazines with the distributor, additional means for rocking the base frames to an extent beyond that controlled by the shifting means so as to locate the lowermost magazine beyond the assembler entrance, and means actuated by said additional means for separating the base frames from each other.

18. In a typographical machine, the combination of a fixed assembler entrance, a plurality of distributor, a corresponding plurality of magazines operatively connected with the distributor, separate base frames whereon the magazines are removably mounted and each pivotally mounted at its upper end immediately adjacent the corresponding distributor, means for shifting the base frames about their respective pivots to bring one or another of the magazines into operative relation to the assembler entrance without affecting the connection of the magazines with the distributor, additional means connected to the lowermost base frame for swinging it relatively to the shifting means to locate the magazine there-

on beyond the assembler entrance, and connections actuated by said additional means for swinging an upper base frame to a still further extent to separate it from the underlying magazine.

19. In a typographical machine, the combination of a fixed assembler entrance, a plurality of distributers, a corresponding plurality of magazines operatively connected with the distributers, separate base frames whereupon the magazines are removably mounted and each pivotally mounted at its upper end immediately adjacent the corresponding distributer, means for shifting the base frames about their respective pivots to bring one or another of the magazines into operative relation to the assembler entrance without affecting the connection of the magazines with the distributers, a pair of cams for swinging the lower base frame relatively to the shifting means to locate the magazine thereon beyond the assembler entrance, and connections between said cams and an upper base frame for swinging the latter to a further extent to separate it from the underlying magazine.

20. In a typographical machine, the combination of a fixed assembler entrance, a plurality of distributers, a corresponding plurality of magazines operatively connected with the distributers, separate base frames whereon the magazines are removably mounted and each pivotally mounted at its upper end immediately adjacent the corresponding distributer, means for shifting the base frames about their respective pivots to bring one or another of the magazines into operative relation to the assembler entrance without affecting the connection of the magazines with the distributers, a pair of cams journaled to the lower base frame and arranged to coöperate with rollers on the machine frame for swinging said base frame relatively to the shifting means to locate the magazine thereon beyond the assembler entrance, and connections between said cams and an upper base frame for swinging the latter to a further extent to separate it from the underlying magazine.

21. In a typographical machine, the combination of a fixed assembler entrance, a plurality of distributers, a corresponding plurality of magazines operatively connected with the distributers, separate base frames whereupon the magazines are removably mounted and each pivotally mounted at its upper end immediately adjacent the corresponding distributer, means for shifting the base frames about their respective pivots to bring one or another of the magazines into operative relation to the assembler entrance without affecting the connection of the magazines with the distributer, and additional mechanism for swinging the base frames upwardly as a whole rela-

tively to the shifting means and separating the base frames from each other.

22. In a typographical machine, the combination of a fixed assembler entrance, a plurality of distributers, a corresponding plurality of magazines operatively connected with the distributers, separate base frames whereon the magazines are removably mounted and each pivotally mounted at its upper end immediately adjacent the corresponding distributer, means for shifting the base frames about their respective pivots to bring one or another of the magazines into operative relation to the assembler entrance without affecting the connection of the magazines with the distributers, additional mechanism for swinging the base frames upwardly as a whole relatively to the shifting means and separating the base frames from each other, and counterbalancing devices connected to said mechanism to facilitate its operation, the connections being such that when said mechanism is at rest the counterbalancing devices act to overcome the weight of the magazines and thus to assist in the operation of the shifting means.

23. In a typographical machine, the combination of a fixed assembler entrance, a plurality of distributers, a corresponding plurality of magazines operatively connected with the distributers, separate base frames whereon the magazines are removably mounted and each pivotally mounted at its upper end immediately adjacent the corresponding distributer, means for shifting the base frames about their respective pivots to bring one or another of the magazines into operative relation to the assembler entrance without affecting the connection of the magazines with the distributers, a pair of rotary cams journaled to the lower base frame and arranged to coöperate with rollers on the machine frame to swing the base frames and magazines thereon as a whole upwardly above the level of the assembler entrance, and counterbalancing devices connected to said cams to assist in their rotation, the connections being such that when said cams are at rest, the counterbalancing devices assist in the operation of the shifting means.

24. In a typographical machine, the combination of a fixed assembler entrance, a plurality of distributers, a corresponding plurality of magazines operatively connected with the distributers, separate base frames whereon the magazines are removably mounted and each pivotally mounted at its upper end immediately adjacent the corresponding distributer, means for shifting the base frames about their respective pivots to bring one or another of the magazines into operative relation to the assembler entrance without affecting the connection of the magazines with the distributer, and additional mechanism for swinging the base frames upwardly as a whole rela-

- the magazines with the distributor, and additional mechanism for swinging the base frames relatively to the shifting means and for separating the base frames from each other, the said means comprising the pair of cams J , the transverse rock shaft J^1 mounted in bearings of the lowermost base frame, and the links J^2 pivoted respectively to the cams J and an upper base frame.
- 10 25. In a typographical machine, the combination of a fixed assembler entrance, a plurality of distributor, a corresponding plurality of magazines operatively connected with the distributor, separate base frames whereon the magazines are removably mounted and each pivotally mounted at its upper end immediately adjacent the corresponding distributor, and means for shifting the base frames about their respective pivots to bring one or another of the magazines into operative relation to the assembler entrance without affecting the connection of the magazines with the distributor, the said means comprising a toggle system arranged 20 at the lower end of the magazines and acting in its extended condition to bring one magazine into operative position and in its collapsed condition to bring a different magazine into operative position, and a hand lever connected to said toggle system and acting by its operation to effect the extension or collapse thereof as required.
26. In a typographical machine, the combination of a fixed assembler entrance, a plurality of distributor, a corresponding plurality of magazines operatively connected with the distributor, separate base frames whereon the magazines are removably mounted and each pivotally mounted at its upper end immediately adjacent the corresponding distributor, and means for shifting the base frames about their respective pivots to bring one or another of the magazines into operative relation to the assembler entrance without affecting the connection of the magazines with the distributor, the said means comprising a toggle system arranged 30 at the lower end of the magazines and acting in its extended condition to bring one magazine into operative position and in its collapsed condition to bring a different magazine into operative position, and a hand lever connected to said toggle system and acting by its operation to effect the extension or collapse thereof as required.
- 35 40. In a typographical machine, the combination of a fixed assembler entrance, a plurality of distributor, a corresponding plurality of magazines operatively connected with the distributor, separate base frames whereon the magazines are removably mounted and each pivotally mounted at its upper end immediately adjacent the corresponding distributor, and means for shifting the base frames about their respective pivots to bring one or another of the magazines into operative relation to the assembler entrance without affecting the connection of the magazines with the distributor, the said means comprising a toggle system arranged 45 at the lower end of the magazines and acting in its extended condition to bring one magazine into operative position and in its collapsed condition to bring a different magazine into operative position, and a hand-lever connected to said toggle system and acting by its operation to effect the extension or collapse thereof as required, and cushioning devices connected to said toggle system and acting to retard the collapsing movement thereof.
- 50 55. In a typographical machine, the combination of a fixed assembler entrance, a plurality of distributor, a corresponding plurality of magazines operatively connected with the distributor, separate base frames whereon the magazines are removably mounted and each pivotally mounted at its
- upper end immediately adjacent the corresponding distributor, and means for shifting the base frames about their respective pivots to bring one or another of the magazines into operative relation to the assembler entrance without affecting the connection of the magazines with the distributor, the said means comprising the toggle members H and H^1 , the rod H^2 to which they are connected, and the hand-lever H^4 , H^6 connected to the rod H^2 .
28. In a typographical machine, the combination of a fixed assembler entrance, a plurality of distributor, a corresponding plurality of magazines operatively connected with the distributor, separate base frames whereon the magazines are removably mounted and each pivotally mounted at its upper end immediately adjacent the corresponding distributor, and means for shifting the base frames about their respective pivots to bring one or another of the magazines into operative relation to the assembler entrance without affecting the connection of the magazines with the distributor, the said means comprising the toggle members H and H^1 , the rod H^2 to which they are connected, and the hand-lever H^6 connected to the rod H^2 , and the dash-pot H^{10} connected to the rod H^2 .
29. A structure as specified in claim 28, characterized by the fact that the upper toggle members H are forked at their upper ends to permit the magazine base frames to be moved relatively thereto.
30. A structure as specified in claim 29, characterized by the fact that the upper toggle members are formed with hooks h^1 adapted to engage abutments O^6 on the machine frame to prevent the collapse of the toggle members when the base frames are disconnected therefrom.
31. In a typographical machine, the combination of a fixed assembler entrance, a plurality of magazines, separate base frames whereon the magazines are removably mounted, means for shifting the base frames to bring one or another of the magazines into operative relation to the assembler entrance, connections between said shifting means and the magazine base frames adapted to be made and broken by a relative movement of said parts, means for effecting such relative movement, and means for locking the shifting means against operation when disconnected from the base frames.
32. In a typographical machine, the combination of a fixed assembler entrance, a plurality of magazines, separate base frames whereon the magazines are removably mounted, means for shifting the base frames to bring one or another of the magazines into operative relation to the assembler entrance and including a toggle system arranged to be straightened or collapsed to effect such interchange of the magazines and having a free

connection with the base frames so as to permit the latter to be disconnected therefrom, and means to prevent the collapse of the toggle system when the parts are so disconnected.

33. In a typographical machine, a combination of a plurality of magazines, base frames whereon the magazines are removably mounted, means for separating the base frames to facilitate the removal of the magazines, and means arranged at the lower ends of the base frames to insure their proper lateral relative location in the closed condition of said parts, the last mentioned means including gage pieces secured to one base frame and arranged to engage vertical alining surfaces formed on the opposite sides of another base frame.

34. In a typographical machine, a combination of a plurality of magazines, base frames whereon the magazines are removably mounted, means for separating the base frames to facilitate the removal of the magazines, and means for holding the base frames in proper relation to each other when in closed condition, the last mentioned means including gage pieces secured to one of the base frames and arranged to contact with alining surfaces formed on the face of another base frame and to engage laterally with further alining surfaces formed on the sides of the latter base frame.

In testimony whereof, I have affixed my signature hereto.

DAVID S. KENNEDY.
